To all whom it may concern:

Be it known that I, ISIDORE LENDING, a citizen of the United States, residing at New Bedford, in the county of Bristol, and State of Massachusetts, have invented a new, original, and ornamental Design for a Hand Bag, of which the following is a specification, reference being had to the accompanying drawing, forming part thereof.

Figure 1 is a front elevation for hand bag in accordance with my invention;

Figure 2 is a back elevation of the same; and

Figure 3 is an end view of the same.

The hand bag of the present invention provides a single continuous frame member extending around the entire periphery of the body portion of the bag. This frame is of a rounded cross-section and relatively thin in its cross-sectional dimensions presenting an impression of a decorative continuous beading or piping around the bag.

I claim:

The ornamental design for a hand bag substantially as shown and described.

ISIDORE LENDING.
